UNITED STATES PATENT OFFICE.

NOAH WALKER, OF PHILADELPHIA, PENNSYLVANIA.

WIPING MECHANISM.

1,407,104.

Application filed March 1, 1921. Serial No. 448,774.

To all whom it may concern:

Be it known that I, NOAH WALKER, a citizen of the United States, residing at Philadelphia, in the county of Philadelphia and State of Pennsylvania, have invented certain new and useful Improvements in Wiping Mechanism, of which the following is a specification.

In filling jars with plastic material, such as cold cream, it is usually the custom to initially supply a slightly greater quantity of the material to the jars than they are capable of holding, when the lids are applied, and then wipe the excess material from the tops so that the material at the top will be smooth and flush with the tops of the jars. This wiping process prior to my present invention has been done by hand and is not commercially satisfactory for the reason that it is slow and tedious and the resulting work cannot be depended upon to be uniform. Furthermore the hand-wiping operation requires numerous individual handling of the jars and is as a whole expensive.

One object of my invention is to provide an improved mechanism which can be used independently of or in connection with a machine for filling jars with plastic material and will serve to quickly and uniformly wipe the excess material from the tops of the jars and to smooth the top of the material remaining in the jars.

Another object is to construct my improved mechanism so that it will simultaneously and successively wipe and smooth a plurality of jars and so that rows of filled jars can be fed thereto and wiped.

A further object is to make my invention of a durable and strong construction.

These objects and other advantageous ends which will be described hereinafter, I attain in the following manner, reference being had to the accompanying drawings in which—

Figure 1 is a top plan view showing my improved mechanism,

Figure 2 is a transverse sectional elevation taken on the line 2—2 of Figure 1,

Figure 3 is a side elevation looking in the direction of the arrow *x* in Figure 2,

Figure 4 is a side elevation looking in the direction of the arrow *y* in Figure 2,

Figure 5 is a sectional elevation taken on the line 5—5 of Figure 4,

Figure 6 is a fragmentary enlarged section taken on the line 6—6 of Figure 3.

Specification of Letters Patent. Patented Feb. 21, 1922.

Figure 7 is a sectional elevation taken on the line 7—7 of Figure 5 and showing the parts moved into a position to wipe excess of the material from the tops of a row of the jars and to smooth the material so that the upper surface of the material will be flush with the tops of the jars, and

Figure 8 is a view of the same general character as that shown in Figure 7 with the wiping members having been moved into a position so as to discharge the excess material into a trough shape receptacle.

Referring to the drawings, 9 represents a supporting frame having side rails 10 arranged parallel and spaced apart and a bed plate 11 arranged between the side rails and in the present instance this bed plate is fixed and serves as a support for rows of jars 12; said rows extending transversely of the bed plate; the bed plate having side flanges 13 so as to form a shallow channel over which the rows of jars 12 are moved by a conveyor 14; said conveyor in the present instance including chains 15 spaced apart and having connected thereto transverse push bars 16; one of these push bars being located between each row of jars 12 and serving to push and keep in straight alignment, the jars as they are fed out of a filling machine or from any other location; said conveyor in the present instance has an intermittent motion and may be driven by any suitable mechanism not illustrated.

The side rails 10 form the respective mountings for two bearings 17; said bearings having parts 18 adjustable upwardly and downwardly; the parts 18 at their tops being T-shape and serving as a support for two shafts 19 and 20. The shaft 19 is rotated by any suitable mechanism and in the present instance, the drive for this shaft consists of a sprocket wheel 21 and a drive chain 22 in operative engagement with said sprocket wheel. This chain 22 may be driven from any suitable source of power. The shaft 19 has adjustably secured thereto, two sets 23 and 24 of arms arranged at an angle to each other relatively to the axis of the shaft 19, as clearly shown in Figures 1 and 7.

The set of arms 23 has secured thereto, rigid strips of material between which are clamped one edge portion of a strip 25 of flexible resilient material, such as tough rubber. In like manner the set of arms 24 has rigid strips secured thereto between which is clamped the edge portion of a flex-

ible resilient strip 26 preferably of tough rubber. These strips 25 and 26 are normally straight and substantially radial with the axis of the shaft 19, as shown at the upper 5 portion of Figure 8 of the drawings. These strips 25 and 26 during the action of the mechanism as will be hereinafter described, are moved one after the other into engagement with the tops of the jars of each row 10 for the purpose of wiping the excess material from the jars and for smoothing the top of the material remaining in the jars; the strip 25 serving to remove the major portion of the excess material while the strip 26 serves 15 more as a smoother for the material remaining in the jars.

The shaft 19 has a gear wheel 27 secured thereto; said gear wheel meshing with another gear wheel 28; the latter being freely 20 mounted on a portion 29 of the shaft 20 as clearly shown in Figure 6. A sprocket wheel 30 is secured to the gear wheel 28 and a chain belt 31 connects this sprocket wheel 30 with a small sprocket pinion 32 on a 25 roller 33 of small diameter. This roller 33 has bearings in two arms 34 which are secured to the shaft 20. One of the arms 34 has an anti-friction wheel 35 rotatably mounted thereon and adapted to engage a 30 cam 36 which is secured to the shaft 19 as clearly shown in Figures 7 and 8. Two brackets 37, which are secured to the shaft 20, support an overhung weight 38; said weight serving to hold the wheel 35 in contact with the cam 36. It is thus obvious 35 that during the rotation of the shaft 19, the cam 36, due to engagement with the anti-friction wheel 35, will swing the roller 33 downwardly in an arc concentric with the 40 axis of the shaft 20. When the low portion of the cam 36 is brought into engagement with the anti-friction wheel 35, the overhung weight 38 will act to swing the roller 33 upwardly; this action taking place during 45 the operation of my mechanism for a purpose hereinafter described.

A smooth plate 39, which has a forward concave surface, is secured to the brackets 37 and is positioned between the arms 34; 50 the lower edge of the plate 39 being parallel with and nearly touching the roller 33, as clearly shown in Figures 7 and 8. The forward concave surface of the plate 39 is sufficiently close to the shaft 19 that the flexible 55 resilient strips 25 and 26 during their rotation are compelled to be flexed due to the contact of said flexible resilient strips with the concave surface of the plate 39; the strips 25 and 26 also being compelled to engage 60 the roller 33 between the jars and the plate 39. The position of the parts is such that when the roller 33 is in its lowermost position it will occupy a position directly adjacent the rear parts of the tops of the 65 jaws so that a portion of the roller 33 is

above and another below the top edges of the jars of the rows to the rear of which the roller is positioned.

The timing of the parts is such that when the conveyor 14 moves forwardly, the roller 70 33 will be raised to permit a row of the jars to pass thereunder and will then be lowered into the position above mentioned to the rear of the rail; the conveyor stopping when the roller has been lowered. Figure 8 shows 75 the parts in the position with the roller raised ready to move downwardly, and Figure 7 shows the roller in a position lowered so as to be directly in the rear of the row of jars during the wiping and smoothing 80 action. It will be noted that the tops of the jars are in the path of rotation of the flexible resilient strips 25 and 26 so that the strips 25 and 26 will flex as they are passing over the top edge of the jars. 85

A transversely extending trough 40 is supported transversely above the bed plate 11 by posts 41 which are slidable in housings 42; said housing having springs 43 therein upon which the posts 41 rest. The 90 springs may be adjustably moved in the housings by means of adjusting screws 44 as shown in Figure 5. The trough 40 has its rear side 45 arranged upright and its forward side 46 slanting; the upper edge of 95 the side 45 being in the path of movement of the flexible strips 25 and 26.

The operation of my improved mechanism is as follows:—The conveyor 14 operates to intermittently move rows of the jars forwardly and, as each row of jars reaches the position under the shaft 19, the roller 33 will be lowered as above described and the flexible strip 25 will first engage the top edges of the jars of said row and wipe off 100 the major portion of the excess of the plastic material. The plastic material under normal temperature conditions will adhere to the strip 25; the roller 33 and plate 39 serving to prevent the plastic material from the strip 25 from falling off while the strip is in a downwardly extending position. In other words, the roller 33 and plate 39 serve as a wall against which the outer portion of the plastic material on the strip 25 slides during 105 the rotation of the shaft 19. The constantly rotating roller 33, if any of the material should escape from the strip 25 and slide down upon the plate, will serve to re-deposit that material upon the plate 39 so 110 that when the strip 26 engages the roller 33 and plate, it will pick up the accidentally dropped portion of the material and convey it upwardly. 115

It will be noted that since the strip 25 120 wipes the major portion of the excess material from the jars that the strip 26 has a better chance to smooth the material since the adhesion of the material is not so great as when a large body of the material is 130

wiped from the top. The strips 25 and 26 after leaving the plate 39 continue in their rotatable path and wipe against the top edge of the side 45 of the trough 40 and 5 deposit and are stripped of the material so that the material from the flexible strips 25 and 26 is received in the trough 40. When this trough becomes full the material can be removed easily by the attendant placing 10 a scraper and dragging the material out of the end of the trough and this material can again be put in the filling machine or disposed of in any desired manner.

In actual practice it has been found that 15 there is practically no possibility of the material, which is wiped from the tops of the jars, falling or running down over the outside of the jars even in warm weather and when the mechanism is operating on jars 20 filled with cold cream or the like the roller 33 serves as a guard so that if any material accidentally escapes from the flexible strips and slides down on the plate 39, it will be compelled to pass in contact with 25 the upper surface of the roller 33 which rotates toward the plate 39 and thereby keeps the material in contact with the plate 39 until one of the strips 25 or 26 moves around to pick up the material. By having the 30 trough 40 resiliently mounted on the springs 43 the action is not severe on the flexible strips 25 and 26.

While I have described my invention as taking a particular form, it will be understood that the various parts of my invention 35 may be changed without departing from the spirit thereof, and hence I do not limit myself to the precise construction set forth, but consider that I am at liberty to make such 40 changes and alterations as fairly come within the scope of the appended claims.

Having thus described my invention, what I claim as new and desire to secure by Letters Patent is:—

45 1. Mechanism for removing excess material from jars including wiping means; means for effecting relative movement between the jars and wiping means whereby the excess material is transferred to the 50 wiping means; and means co-operative with said wiping means for stripping said material therefrom; substantially as described.

55 2. Mechanism for removing excess material from jars including a movable flexible member for wiping engagement with the tops of the jars whereby the excess material is separated from material in the jars; and means for stripping said excess material from said member during movement of said 60 member; substantially as described.

65 3. Mechanism for removing excess material from jars including a rotatable flexible member for wiping engagement with the tops of the jars whereby the excess material is lifted from the jars on the flexible mem-

ber; and a receptacle for stripping engagement with said member to receive said excess material; substantially as described.

4. Mechanism for removing excess material from jars including a rotatable flexible 70 member for wiping engagement with the tops of the jars whereby the excess material is lifted from the jars on the flexible member; a receptacle for stripping engagement with said member to receive said excess material; and guard means with which said member engages in passing from the jars to said receptacle; substantially as described.

5. Mechanism for removing excess material from jars including a rotatable flexible 80 member for wiping engagement with the tops of the jars whereby the excess material is lifted from the jars on the flexible member; a receptacle for stripping engagement with said member to receive said excess material; and guard means with which said member engages in passing from the jars to said receptacle, said guard means including a plate and a roller adjacent the lower portion of said plate; substantially as de- 85 scribed.

6. Mechanism for removing excess material from jars including means adapted to be positioned in close proximity to the top edges of the jars; and wiping means for 95 wiping the excess material from said jars into contact with said first means whereby said first means serves as a support for said excess material; substantially as de- 100 scribed.

7. Mechanism for removing excess material from jars including means adapted to be positioned in close proximity to the top edges of the jars; wiping means for wiping the excess material from said jars 105 into contact with said first means whereby said first means serves as a support for said excess material during the wiping movement of said wiping means; and a receptacle in which said excess material is de- 110 posited; substantially as described.

8. Mechanism for wiping excess material from jars including means adapted to be positioned in close proximity to the tops of the jars; rotatable wiping means adapted to wipe the excess material off the tops of said jars and push it upwardly over said first means whereby said first means prevents the excess material from falling off said wiping means during a portion of its 115 travel; and a receptacle located in the path of movement of said wiping means into which the excess material is deposited; substantially as described.

9. Mechanism for wiping excess material 125 from jars including means adapted to be positioned in close proximity to the tops of the jars; rotatable wiping means adapted to wipe the excess material off the tops of said jars and push it upwardly over said 130

4
first means whereby said first means prevents the excess material from falling off said wiping means during a portion of its travel, said first means being movable after 5 said wiping action into a position above the tops of said jars; and means for feeding other jars, to be wiped, into the path of action of said wiping means, said first means being operative to be lowered into said first 10 mentioned position relatively to the second mentioned jars; substantially as described.

10. Mechanism for removing excess material from jars including two shafts; wiping means connected to one of said shafts; 15 means for rotating said latter mentioned shaft; means for rocking the other shaft, said latter mentioned shaft having a concave plate thereon; a driven roller adjacent the bottom of said plate whereby when 20 the second mentioned shaft rocks, the roller will be moved into positions directly adjacent the rear and top edges of the jars and out of the path of said jars, said wiping means being adapted to wipe said excess material from the jars and convey it over 25 said plate; and a receptacle into which said wiping means discharges said excess material; substantially as described.

11. Mechanism for removing excess material from jars including two shafts; wiping means connected to one of said shafts; 30 means for rotating said latter mentioned shaft; means for rocking the other shaft, said latter mentioned shaft having a concave plate thereon; a driven roller adjacent the bottom of said plate whereby when 35 the second mentioned shaft rocks, the roller will be moved into positions directly adjacent the rear and top edges of the jars and out of the path of said jars, said wiping means being adapted to wipe said excess material from the jars and convey it over 40 said plate; and a receptacle into which said wiping means discharges said excess material; substantially as described.

12. Mechanism for removing excess ma-

terial from jars including two shafts; wiping means connected to one of said shafts; 50 means for rotating said latter mentioned shaft; means for rocking the other shaft, said latter mentioned shaft having a concave plate thereon; a driven roller adjacent the bottom of said plate whereby when 55 the second mentioned shaft rocks, the roller will be moved into positions directly adjacent the rear and top edges of the jars and out of the path of said jars, said wiping means being adapted to wipe said excess 60 material from the jars and convey it over said plate; and a receptacle into which said wiping means discharges said excess material, said means for rocking said shaft consisting of a cam on said first shaft, a 65 portion connected to said rock shaft for engagement with said cam, and a counterweight for keeping said portion in engagement with said cam; substantially as described.

13. Mechanism for removing excess material from the tops of jars including rotatable wiping means for engagement with the excess material; a concave plate extending upwardly and over which said wiping means moves said excess material during 75 its upward travel; and a receptacle positioned in the path of said wiping means for stripping said material therefrom; substantially as described.

14. Mechanism for removing excess material from the tops of jars including movably mounted wiping means for engagement with the excess material to wipe it from the jars; and a resiliently supported receptacle 85 in the path of movement of said wiping means for receiving the excess material therefrom; substantially as described.

In testimony whereof I have signed my name to this specification in the presence 90 of two subscribing witnesses.

NOAH WALKER.
